GRAPPLING TOOL

Dean W. Osmun, Houston, Tex.

Application September 14, 1954, Serial No. 455,815

3 Claims. (Cl. 294—102)

This invention relates to a grappling tool and more particularly to a grappling tool of the circulating overshot type, known as a short catch overshot, which is designed for use in removing stuck objects, such as pipe and the like, from wells, and which is especially constructed for use under conditions in which there may be only a very limited portion of the stuck object located in a position to be engaged by the tool.

In well drilling and producing operations objects, such as well pipe, are frequently broken off or become disconnected in the well bore, making it necessary to employ a grappling tool to remove the same, and it often happens that only a few inches of the object are in a position to be engaged by the tool to effect a connection by which a pull can be exerted on the object sufficient to remove it from the well.

Grappling tools of the overshot type, as heretofore commonly constructed, have been provided with a cylindrical bowl in which a grapple element or basket is positioned to grippingly engage the exterior of the object when positioned about the same and which is so located that the end of the object must extend into the bowl for a substantial distance before it can be engaged with the basket. Frequently such tools are also provided with tubular guides of substantial length at their lower ends positioned to guidingly engage the object to enable the tool to be easily telescoped over the object.

The present invention has for an important object the provision of a grappling tool of the short catch overshot type having gripping means which is constructed and positioned to form an effective gripping connection with a portion of a stuck object of very limited length whereby a pull may be exerted on the object.

Another object of the invention is to provide a grappling tool of the short catch circulating overshot type having seal forming means which is engageable with the exterior of a stuck well pipe and with the interior of the bowl of the grapple to form a fluid tight seal whereby circulation of fluid may be carried on during the pulling operation.

A further object of the invention is the provision of a grappling tool of the short catch overshot type which embodies guide means positioned to engage the stuck object to aid in the telescoping of the grapple over the object, and whose length does not substantially increase the length of the object which must be available for gripping engagement with the tool.

A further object of the invention is to provide a grappling tool of the short catch overshot type having a tubular bowl provided with an inside downwardly tapering seat and an expandable tubular grapple in the bowl having an external downwardly tapering face conforming to the seat and engageable therewith to contract the grapple into gripping engagement with a stuck object upon relative longitudinal movement of the grapple and bowl.

Another object of the invention is the provision of a grappling tool of the short catch overshot type having a bowl and grapple structure of the kind described and also

2

having guide means on the bowl which is engageable with a stuck object to guide the object into the grapple and which is positioned for engagement with the grapple to limit downward movement of the grapple relative to the bowl.

A still further object of the invention is to provide a grappling tool of the short catch overshot type which is of simple design and rugged construction, which may be economically manufactured and wherein the parts are easily replaceable.

The above and other important objects and advantages of the invention may best be understood from the following detailed description, constituting a specification of the same, reference being had to the annexed drawings, wherein—

Figure 1 is a vertical, central, cross-sectional view of the tool;

Figure 2 is a cross-sectional view, taken along the line 2—2 of Figure 1, looking in the direction indicated by the arrows; and

Figure 3 is a side elevational view of the grapple element of the tool.

Referring now to the drawings in greater detail, wherein like numerals of reference designate the same parts throughout the several views, the numeral 10 designates a tubular coupling member whose upper end is internally threaded to receive the lower end 12 of an operating string of pipe which extends upwardly to the ground surface. The coupling member has an externally reduced lower end portion 14 which is externally threaded for connection to the upper internally threaded end portion of a tubular bowl 16. The coupling member also has internal and external bevelled end surfaces 18 and 20, respectively, at its lower end for a purpose later to be made apparent.

The lower end of the bowl is provided with an internal bevelled end glide surface 22 and a counterbore 24, located inwardly of the glide surface 22 within which a ring 26 is seated, the ring being secured in the counterbore by means of welding as indicated at 28, and forming an upwardly facing internal annular shoulder 27 providing an abutment against which the lower end of the grapple may rest to limit downward movement of the grapple in the bowl. The metal of the weld 28 is smoothed to form a continuation of the bevelled surface 22.

Above the counterbore 24 the bowl is formed with a downwardly tapering seat 30 which may take the form of a spiral forming a downwardly facing shoulder 32.

A tubular expandable grapple 34 is positioned in the bowl for longitudinal movement therein and has an external downwardly tapering face 35 shaped to conform to and ride upon the seat 30. This tapering face 36 terminates in an upwardly facing external shoulder 38, arranged in opposed relation to the downwardly facing internal shoulder 32 of the bowl.

The grapple has a longitudinal slit 40 therethrough which is provided with a widened upper end portion 42, whereby the grapple is rendered expandable, and the interior of the grapple is toothed as indicated at 44, for gripping engagement with the exterior of a well pipe or other stuck object which may be extended into the grapple. Other longitudinal slits, such as that shown at 41, are also provided at circumferentially spaced intervals in the grapple, which terminate at one end inwardly of the end of the grapple and whereby the grapple is rendered more easily contractible and expandable while at the same time being formed in one piece. The grapple may also have an internal tapering lower end surface 43 to aid in guiding the end of a stuck object into the grapple.

Above the seat 30 the bowl is formed with an internal upwardly facing shoulder 46, and within the bowl an annular grapple control 48 is positioned in engagement at

its lower end with the shoulder 46 and whose upper end is formed with an internal bevelled end face 50 positioned for engagement with the external bevelled lower end surface 20 of the coupling member 10, whereby the control is retained in position in the bowl. The grapple control has an external annular groove 52, for the reception of suitable packing means, such as the O-ring 54 which forms a fluid tight seal between the control and the bowl. Within the grapple control there is an internal annular groove 56 within which a seal ring 58 is seated in position to form a fluid tight seal between the overshot and the exterior of the stuck object engaged thereby.

At its lower end the grapple control has a downwardly extending key 60 positioned to extend into the enlarged upper end portion 42 of the slit 40 of the grapple. The key 60 also extends into an internal longitudinal groove or keyway 62 in the bowl, to hold the control and grapple against rotation relative to the bowl.

The tool may be assembled by first inserting the grapple in the upper end of the bowl 16 and screwing the grapple downwardly into position with the downwardly tapering external face 36 thereof in contact with the internal downwardly tapering seat 30 of the bowl. The grapple control is then inserted in the bowl above the grapple with the key 60 thereof extending into the widened upper end portion 42 of the slit 40 of the grapple and the keyway 62 of the bowl. The bowl may then be connected to the lower end 12 of the tubular string and the tool lowered into the well bore.

By lowering the tool in the well bore on the string the lower end of the tool may be guided over the object to be pulled which will be guided into the grapple by engagement with the internal tapering lower end surface 22 of the bowl. After the grapple has passed over the object it will grip the same, and upon upward movement of the tool, the seat 30 will move upwardly relative to the external face 36 of the grapple, thus contracting the grapple into secure gripping engagement with the object so that an upward pull may be taken on the object to remove the same from the well. It will be apparent that only a very short portion of the upper end of the object need be so located as to enter the grapple in order to enable the tool to be effectively used to grip the object sufficiently to exert an upward pull thereon.

The ring 26 may extend radially inwardly of the bowl a sufficient distance so that the lower end of the grapple will not pass through the ring when fully contracted and should the upward pull on the operating string be great enough to result in crushing or distortion of the stuck object and to cause the grapple to collapse, then the lower end of the grapple will engage the ring to prevent the grapple from being pulled downwardly out of the bowl. In the event that a longer portion of the upper end of the object is positioned to enter the tool, the tool may be lowered over the object until it extends upwardly into the control 48 through the seal ring 58, whereupon fluid may be circulated through the string and the object.

Should it be desired to release the tool from the object the tool may be lowered and when the bowl reaches the limit of its downward movement relative to the grapple the grapple which remains engaged with the object, may expand, and the grapple and bowl may be rotated in an appropriate direction to unscrew the threads 44, to thread the grapple off of the object.

It will thus be seen that the invention, constructed and operated in the manner described above provides a grapping tool of the short catch overshot type, which is of simple design and which is readily engageable with stuck objects which are so constructed or positioned that only a few inches of the upper end of the object is available for gripping engagement with the grapple, but which may

also be used to connect a tubular string with an object having a longer portion available for such gripping engagement, so that circulation through the string and object may be established.

While the invention has been disclosed herein in connection with a certain specific embodiment of the same, it will be understood that this is intended by way of illustration only, and that various changes in the construction and arrangement of the parts can be made without departing from the spirit of the invention or the scope of the appended claims.

Having thus clearly shown and described the invention, what is claimed as new and desired to secure by Letters Patent is:

1. An overshot to telescope over an object to be withdrawn from a well and comprising a tubular bowl connected to an operating string of pipe and having an inside downwardly and inwardly tapering seat and an inside longitudinal keyway, a tubular expansible grapple in the bowl having a longitudinal side slot and an external downwardly and inwardly tapering face to conform to the contour of, and to rest on said seat, a controlling member in the bowl above the grapple and including a key seated in the keyway and extending into said side slot, and means on the bowl below the seat extending radially inwardly of the inner wall of the bowl in position for endwise abutting engagement with the lower end of the grapple when the grapple is in contracted condition to limit downward movement of the grapple in the bowl.

2. An overshot to telescope over an object to be withdrawn from a well and comprising a tubular bowl connected to an operating string of pipe and having an inside downwardly and inwardly tapering seat and an inside longitudinal keyway, said bowl also having an inside tapering lower end face and a counterbore extending inwardly from said face, means in the counterbore having an inside tapering surface forming a continuation of said end face and extending radially inwardly beyond said seat, a tubular expansible grapple in the bowl whose lower end is positioned for engagement with said means to limit downward movement of the grapple in the bowl, said grapple having a longitudinal side slot and an external downwardly and inwardly tapering face to conform to the contour of and rest on said seat, and a controlling member in the bowl above said grapple and including a key seated in the keyway and extending into said side slot in position for engagement with the bowl and grapple to hold the bowl and grapple against relative rotation.

3. An overshot to telescope over an object to be withdrawn from a well and comprising a tubular bowl connected to an operating string of pipe and having an inside downwardly and inwardly tapering seat and an inside longitudinal keyway, a tubular expansible grapple in the bowl having a longitudinal side slot and an external downwardly and inwardly tapering face to conform to the contour of, and to rest on said seat, an annular controlling member in the bowl above said grapple and including a key seated in the keyway and extending into said side slot, means in the bowl positioned to engage the exterior of said member and the interior of the bowl to form a fluid tight seal between the member and bowl, said member having an inside annular groove and a seal forming element in said groove in position to engage an object extending into said member to form a fluid tight seal between the member and object.
